UNITED STATES PATENT OFFICE.

OTTO H. L. DESWATINES, OF NEW YORK, N. Y.

LIFE-BOAT.

1,125,270.

Specification of Letters Patent. Patented Jan. 19, 1915.

Application filed May 15, 1912. Serial No. 697,549.

To all whom it may concern:

Be it known that I, OTTO H. L. DESWATINES, a subject of the German Emperor, residing at New York, in the county of New York and State of New York, have invented certain new and useful Improvements in Life-Boats, of which the following is a specification.

The present invention has for its object 10 to provide a life boat which will be non-sinkable and in which there is a separate compartment for each passenger arranged apart from one another so that if by accident one or more are damaged or destroyed, 15 the others will not be affected.

Another object of my invention is to secure to each compartment a water proof cover or hood which the occupant may slip over the upper part of his body so as to 20 protect himself against cold, rough seas, etc.

With these objects in view my invention consists in the construction, combination and arrangement of parts as will be herein-after specified and set forth in the appended 25 claim.

In the accompanying drawing, which forms a part of this specification, similar reference letters denote corresponding parts and Figure 1 is a top plan view; Fig. 2 a 30 side elevation partly in section and Fig. 3 a cross section of the boat on line 3—3 of Fig. 1 and Fig. 4 an enlarged detail of a cover or hood.

1 denotes a boat which may be of any 35 suitable shape and may be constructed as a row boat, sail boat or motor boat. In the present embodiment of my invention the life boat is shown as a row boat. The interior of the boat is closed upon top by an 40 air tight and water proof deck 2 in which a number of holes 3, 4 are provided. These holes lead into compartments 5, 6 formed as tubular pockets or casings secured to the deck and extending downwardly into the 45 interior of the boat. These casings are closed at the bottom and serve partly for the accommodation of passengers and partly as storage receptacles for food or other articles.

The compartments 5 which serve to accommodate passengers are provided with seats 50 7. The different compartments are arranged apart from each other and the space 8 between the different compartments and the bottom may serve to receive compressed air through suitable valves (not shown) ar- 55 ranged in the deck 2.

Secured around the upper edge of each passenger compartment may be a cover or hood 9 (Figs. 2-4) of waterproof material and suitable construction which the occupant may slip around the upper part of his body to protect himself against cold, 60 rough seas, etc.

If the boat is constructed as a row boat, as in the present example, there may be 65 formed in the deck 2 receptacles 10 for the accommodation of the oars, when not in use.

The boat may be formed with several bottoms 11, 12, 13 which by spaces 14 are separated from one another. These spaces may be either air spaces or may be filled with cork or the like.

Since various modifications may be made in the construction without departing from 75 the spirit of my invention I do not wish to restrict myself to the particular details described and shown.

What I claim and desire to secure by Letters Patent is:

A life boat having an upper air tight and 80 water proof deck formed with a number of perforations tubular compartments fixed to said deck and extending from said perforations into the boat, the compartments 85 having each a separate bottom, and the space between each compartment and between the deck and the bottom of the boat being filled with compressed air.

In testimony whereof I affix my signature 90 in presence of two witnesses.

OTTO H. L. DESWATINES.

Witnesses:

MAX D. ORDMANN,
JOHN T. CARMODY.
